UNITED STATES PATENT OFFICE.

HARRY B. REDDING, OF COLUMBUS, OHIO, ASSIGNOR, BY DIRECT AND MESNE ASSIGNMENTS, OF TWO-THIRDS TO I. S. FINK, OF COLUMBUS, OHIO.

VALVE.

1,370,225.

Specification of Letters Patent.

Patented Mar. 1, 1921.

Application filed January 16, 1920, Serial No. 351,802. Renewed September 3, 1920. Serial No. 407,911.

To all whom it may concern:

Be it known that I, HARRY B. REDDING, a citizen of the United States, residing at Columbus, in the county of Franklin and State 5 of Ohio, have invented certain new and useful Improvements in Valves, of which the following is a specification.

This invention relates to improvements in valves, and has particular reference to the 10 casing formation of hand operated valves in particular, the object of the invention being to provide a valve casing wherein is embodied an improved stem supporting and guarding structure, which latter is formed 15 in a manner which is very economical to produce and is substantial, effective and practical in operation and service.

For a further understanding of the invention, reference is to be had to the following 20 description and to the accompanying drawings, in which:

Figure 1 is a side elevation of a valve casing constructed in accordance with the principles of the present invention.

25 Fig. 2 is an edge elevation of said casing.

Fig. 3 is a vertical sectional view taken along the line 3—3 of Fig. 2.

Fig. 4 is a transverse sectional view taken along the line 4—4 of Fig. 3.

30 Fig. 5 is a similar view taken along the line 5—5 of Fig. 3.

Fig. 6 is a detail view of the stock from which the stem supporting standard is formed.

35 Fig. 7 is a similar view showing the manner in which the standard is expanded, and,

Fig. 8 is a view showing the completed standard.

In carrying out the steps of my invention, 40 use is made of a valve casing 1, which consists essentially of a vertical closure receiving portion 2 and intercepting fluid conduits 3. The outer ends of the conduits may be equipped with flanges 4 by means of which 45 pipes or other suitable fluid conducting elements may be connected with the casing. The steps taken in the construction of this casing have been particularly described in my co-pending application bearing Serial 50 Number 351,801, and filing date January 16, 1920, and accordingly, the casing 1 does not in itself form any part of the present invention.

The upper end of the portion 2 is pro-

vided with an out-turned flange 5 upon 55 which is mounted the base member 6 of a stem supporting structure 7. The member 6 is preferably formed from a flat blank of metal and may have its edges provided with suitable openings for the reception of securing elements, which are employed as usual for the purpose of securely fastening the supporting structure 7 to the casing 1. The member 6 is further formed with a central opening through which projects the 60 upper threaded end of a valve stem 8, by means of which a valve structure (not shown) situated in the portion 2 may be actuated. Preferably a packing 9 is provided for the purpose of surrounding the 65 stem 8 at a point where the latter projects through the base member 6, and said packing functions in the customary manner to prevent undue escape of fluid from the valve casing 1. The packing 9 may be contained 70 within a cup 10 integrally formed upon the outer surface of the base member, and a nut 11 may be telescopically mounted within the cup 10 for the purpose of applying suitable pressure to the packing 9, as will be 75 clearly understood.

The stem supporting structure 7 further includes a standard 12 which is formed to embody an upper tubular portion 13 and downwardly and outwardly flaring leg members 14, the lower end of the latter being welded to the base member 6 for the purpose of providing a secure and substantial support. If desired, a bushing 15 may be inserted within the tubular portion 13 and 80 suitably secured therein so that the upper portion of the standard 12 will be materially reinforced. An internally threaded nut 16 is threaded positioned upon the upper end of the stem 8, and is connected with 85 a hand wheel 17 by means of a set screw or the like 18 whereby upon the rotation of said wheel, said nut will be revolved in unison therewith and the stem 8 will be raised and lowered in the conventional manner. 90 The hub of the wheel 7 is situated so as to rest upon the upper circular edges of the tubular portion 13 and the bushing 15 and is thus insured of a positive and substantial seat, while the lower end of the nut 16 is 95 provided with an out-turned collar 19, which extends into engagement with the lower edge of the bushing 15. Thus by the presence of 100 105

the bushing, said nut will be prevented from being raised or lowered upon the rotation of the wheel 17.

The present invention consists essentially 5 in the standard construction 12 which as will be observed is of such formation as to substantially enhouse the threaded end of the valve stem and also to provide a permanent and effective seat for the wheel 17 and 10 its component parts. This standard is formed as shown in Fig. 6, from a suitable length of tubular stock, which is cut or otherwise operated upon so as to produce registering slots 20 therein. These slots are 15 of relatively greater width than their upper ends, and their sides 21 converge toward the center of the stock, and in fact are brought into engagement with each other at the lower end of the standard, so that said 20 slots when initially formed and cut from the standard will be of substantially triangular formation. The next step in operation is to spread the lower ends of the standard so as to produce the downwardly and 25 outwardly flaring leg members 14 until the same have assumed such positions as will be advantageous in connecting the same with the base member 6. Then to flatten the lower ends of the leg members and to expand their 30 general width at the lower ends thereof, said leg members are flattened as at 22 to produce the configuration clearly disclosed in Fig. 8 of the drawings. When this form has been reached, the lower ends of said 35 standard are positioned properly upon the upper surface of the base member 6, and are then welded thereto, so that the said base member and standard when completed will be of substantially an integral, homogeneous 40 and substantial construction.

It will be manifest that by virtue of the

construction described the process of forming the super-structure of a valve casing will be considerably facilitated. The standard produces a maximum degree of strength 45 and rigidity and is exceptionally light in weight. This is the result of eliminating castings and other similar heavy formations, and may be effectively used for the purpose of supporting a valve stem and its actuating wheel in lieu of such cast formations.

I claim:

1. The herein described method for producing valve stem supporting standards, 55 which consists in the provision of a metallic tube of suitable dimensions, in providing registering slots of tapering configuration in the opposite sides of said tube, said slots being terminated at one end of said tube, in 60 flaring the portions of said tube in an outward direction so as to produce downwardly and outwardly converging leg members, and in welding said leg members to the base member.

2. The herein described method for producing valve stem standards, which consists in the provision of a metal tube, in producing elongated tapering slots in the length of said tube, said slots having their lower converging ends terminated at one end of said tube and their other relatively broadened ends in spaced relation from the other end of said tube whereby a sleeve is produced in said latter end, in spreading the portions 75 of said tube surrounding said slots in an outward direction so as to produce downwardly and outwardly extending leg members, and in securing said leg members by a welding 80 process to the base member.

In testimony whereof I affix my signature.

HARRY B. REDDING.
